[57] **CLAIM**

The ornamental design for a light bulb extractor, as shown and described.

DESCRIPTION

FIG. 1 is a diagrammatic perspective view of the light bulb extractor;

FIG. 2 is an enlarged front elevational view thereof;

FIG. 3 is an enlarged rear elevational view thereof;

FIG. 4 is a left side elevational view thereof, the right side elevational view being a mirror image of the left side view;

FIG. 5 is a bottom plan view thereof; and,

FIG. 6 is a top plan view of the light bulb extractor.
